(57) **CLAIM**

The ornamental design for a medical dressing, as shown and described.

DESCRIPTION

FIG. 1 is a perspective top view of an ornamental design for a medical dressing.

FIG. 2 is a top view of the medical dressing of FIG. 1. FIG. 3 is a bottom view of the medical dressing of FIG. 1. FIG. 4 is a right side view of the medical dressing of FIG. 1, the left side being a mirror thereof.

FIG. 5 is a rear view of the medical dressing of FIG. 1; and, FIG. 6 is a front view of the medical dressing of FIG. 1. The medical dressing is shown with a symbolic break in its length. The appearance of any portion of the article beyond the break lines forms no part of the claimed design. The broken lines illustrate portions of the medical dressing which form no part of the claimed design.
